UNITED STATES PATENT OFFICE.

MARK H. MARTIN, OF BALTIMORE, MARYLAND, ASSIGNOR TO THE SYMINGTON COMPANY, OF NEW YORK, N. Y., A CORPORATION OF MARYLAND.

SIDE FRAME.

Application filed June 30, 1925. Serial No. 40,529.

This invention relates to side frames for railway car trucks and more particularly to the construction of the ends of cast side frames with integral journal boxes.

5 The principal object of my invention, generally considered, is the reinforcement of the union between integral journal boxes and the adjacent ends of cast side frames for railway car trucks.

10 An object of my invention is the strengthening of the junction between integral journal boxes formed at the ends of side frames for railway car trucks by reinforcing the lower flanges on the tension member of such trucks and extending said reinforcement beyond the junctions with the journal boxes and along the roofs thereof.

Another object of my invention is the 20 rigidifying of the end construction of cast side frames with journal boxes integral therewith and particularly of such side frames in which the compression and tension members are substantially T or I shape in cross-section, by providing upstanding ribs 25 or flanges along the outer edges of the lower flanges and of the tension member, said ribs being continued past the junction between the side frame and journal box over the roof of each journal box.

30 A further object of my invention is the provision of a special reinforcement adjacent the junction between integral journal boxes and the ends of cast side frames, said side frames preferably comprising a tension member formed with upright web portions and lower flange portions, said flange portions being united with the journal boxes adjacent the upper inner corners thereof and reinforced by upstanding ribs, preferably along the outer edges thereof, and longitudinally disposed, said ribs being extended from below the junction between the flange and journal box past said junction and continued over a substantial portion of 40 the roof of the journal box, the strength of said ribs being preferably greatest adjacent the junction between the flange and journal box and decreasing both ways toward the ends thereof.

45 Other objects and advantages of the in-

vention relating to the specific arrangement and construction of the various parts will become apparent as the description proceeds.

Referring to the drawings illustrating my invention, the scope whereof is defined by the 55 claims:

Figure 1 is a fragmentary side elevation of an end of a cast side frame for railway car trucks, a portion thereof being shown in section; and

Figure 2 is a plan view of that portion of the side frame shown in Figure 1.

Referring specifically to the drawings in which like reference characters designate like parts, there is illustrated one end of 65 a cast side frame 1 formed with a compression member 2, tension member 3, and integral journal boxes 4. As will be understood, both ends of the frame are similar, said frame being formed, as is usual, with 70 a compression member 2 and a tension member 3 extending substantially the full length thereof and integrally united at the ends of said frame to each other and to the journal boxes, the intermediate portions of said compression and tension members being spaced by bolster column or strut portions, not shown. Certain of the aforementioned features being of usual and well known construction and not part of my present invention, 75 are not illustrated.

In the present embodiment of my invention the compression and tension members are both substantially T or I shape in cross-section, that is, the compression member 85 comprises a substantially upright web portion 5, an upper or outer relatively wide flange portion 6, and a lower or inner relatively narrow and preferably tapering flange or rib portion 7. Likewise, the tension member 3 comprises a lower or outer relatively wide flange portion 8 united to a relatively narrow and preferably tapering upper or inner flange portion 9 by a substantially upright web portion 10. The web 90 portions 5 and 10 of the compression and tension members, respectively, merge at their ends with each other and with the roof or upper wall 11 of the journal box 4. The flange or rib portions 7 and 9 likewise are 100

curved and merge together at the outer corners of the triangular openings 12 in the side frame.

The upper flange 6 of the compression member in the present instance is curved downwardly at its ends and unites with the roof of each journal box 4 substantially in line with the outer brass lug 13. The lower flange 8 of the tension member 3 extends 10 diagonally upward and unites with the roof 11 of the journal box 4, in the present instance, substantially in line with the inner brass lug 14 although I do not wish to be limited to the exact point of union of said 15 flange with the journal box 4. The journal box 4 may be braced and rigidly united to the lower surface of the flange 8 by a triangular web or gusset portion 15 extending between said flange 8 and the inner wall 16 20 of the journal box 4. Said triangular reinforcement may comprise a longitudinal substantially upright web 17 and a substantially horizontal flange portion 18 merging at its ends with the flange 8 and the wall 16 of 25 the journal box.

The flange 8 of the tension member is additionally reinforced and the union of the frame with the journal box materially strengthened by upstanding longitudinally 30 extending ribs or flanges 19, preferably formed on the outer or free edges of said flange 8 and extending from a point materially below the union of said flange and journal box, beyond the union of the flange 35 and journal box, and continuing over the roof of said journal box for a substantial portion of the extent thereof.

As will be appreciated from a consideration of Figure 1 particularly, the ribs 19 preferably gradually increase in strength, height or width to a maximum adjacent the junction between the flange 8 and journal box 4 and from there decrease in strength, height or width to the ends of said ribs adjacent 40 the outer portions of the journal box roofs. Although said reinforcing ribs or flanges 19 are shown as preferably curved over the junction with the journal box, I do not wish to be restricted to this showing for 45 said flanges may be of different formations and positioned differently from the construction illustrated, the showing in the present instance being merely a preferred embodiment of my invention, as will be understood.

50 The outer end portions of the flanges 19 are preferably braced and connected to the web portion 5 of the side frame by tapering or sloping webs 20 merging at their inner ends with the web 5 and at their outer ends 55 with the ribs 19.

In view of the foregoing construction it will be appreciated that I have devised a reinforcement for the lower flange of the tension member and the junction between

said flange and tension member with the integral journal boxes of cast side frames, 65 said reinforcement serving to rigidify the structure at the union between the journal boxes and side frame and causing the flange metal to work more nearly as a unit with the 70 metal in the journal box roof, thereby greatly strengthening the frame at these points.

Having now described my invention, I claim:

1. A car truck side frame comprising a 75 tension member, a compression member, said members being generally T-shape in section, with the web of the section arranged in substantially upright position, journal boxes at the ends of the frame, the lower flange of 80 the tension member joining each journal box roof at approximately the upper corner of the inner brass lug and reinforced adjacent said junction by longitudinal upright ribs.

2. A car truck side frame comprising a 85 tension member, a compression member, said members being generally T-shape in section, with the web of the section arranged in substantially upright position, journal boxes at the ends of the frame, the lower flange of the 90 tension member joining each journal box roof at approximately the upper corner of the inner brass lug and reinforced adjacent 95 said junction by longitudinal upright ribs, said ribs extending from a substantial distance below the junction with each journal box and continuing beyond said junction for a substantial distance over the roof of each journal box.

3. A car truck side frame comprising a 100 tension member, a compression member, said members being generally T-shape in section, with the web of the section arranged in substantially upright position, journal boxes at the ends of the frame, the lower flange of 105 the tension member joining each journal box roof at approximately the upper corner of the inner brass lug and reinforced adjacent said junction by longitudinal flanges disposed along the free edges thereof. 110

4. A car truck side frame comprising a tension member, a compression member, said members being generally T-shape in section, with the web of the section arranged in substantially upright position, journal boxes at 115 the ends of the frame, the lower flange of the tension member joining each journal box roof at approximately the upper corner of the inner brass lug and reinforced adjacent 120 said junction by longitudinal ribs extending upwardly from said lower flange along approximately the free edges thereof.

5. A car truck side frame comprising a tension member, a compression member, said members being generally T-shape in section, 125 with the web of the section arranged in substantially upright position, journal boxes at the ends of the frame, the lower flange of the

- tension member joining each journal box roof at approximately the upper corner of the inner brass lug and reinforced adjacent said junction by longitudinal flanges disposed along the free edges thereof, extending from below the junction with each journal box, gradually increasing in strength to approximately said junction and continuing beyond said junction over the roof of said journal box, gradually decreasing in strength to the ends thereof.
6. A car truck side frame comprising a tension member, a compression member, said members being generally T-shape in section, with the web of the section arranged in substantially upright position, journal boxes at the ends of the frame, the lower flange of the tension member joining each journal box roof at approximately the upper corner of the inner brass lug and reinforced adjacent said junction by longitudinal ribs extending upwardly from said lower flange along approximately the free edges thereof, said ribs extending from a substantial distance below the junction with each journal box, curved over said junction and continued over a substantial portion of the roof of each journal box, the strength of each rib being greatest adjacent the junction with the journal box and decreasing therefrom to the ends.
7. A car truck side frame comprising a tension member, a compression member, said members being generally T-shape in section, with the web of the section arranged in substantially upright position, journal boxes at the ends of the frame, the lower flange of the tension member joining each journal box roof at approximately the upper corner of the inner brass lug and reinforced adjacent said junction by longitudinal upright ribs, said ribs being braced and connected to the web of the compression member at intermediate portions thereof by transverse connecting webs.
8. A car truck side frame comprising a tension member, a compression member, said members comprising substantially upright web portions and upper and lower flanges, journal boxes at the ends of the frame, the lower flange of the tension member intersecting and joining each journal box, and reinforced by local upstanding ribs adjacent the ends of said flange.
9. A car truck side frame comprising a tension member, a compression member, said members comprising substantially upright web portions and upper and lower flanges, journal boxes at the ends of the frame, the lower flange of the tension member intersecting and joining each journal box, and reinforced by local upstanding ribs adjacent the ends of said flange, said ribs increasing in strength from the ends to intermediate portions thereof, and being of maximum strength adjacent the junctions between said flange and journal boxes.
10. A car truck side frame comprising a tension member, a compression member, said members comprising substantially upright web portions and upper and lower flanges, journal boxes at the ends of the frame, the lower flange of the tension member intersecting and joining each journal box, and reinforced by local upstanding ribs adjacent the ends of said flange, said ribs increasing in strength from the ends to intermediate portions thereof, and being of maximum strength adjacent the junctions between said flange and journal boxes.
11. A car truck side frame comprising a tension member, a compression member, said members comprising substantially upright web portions and upper and lower flanges, journal boxes at the ends of the frame, the lower flange of the tension member intersecting and joining each journal box, and reinforced by local upstanding ribs adjacent the ends of said flange, said ribs increasing in strength from the ends to intermediate portions thereof, and being of maximum strength adjacent the junctions between said flange and journal boxes, extending along the free edges of said flange, and continuing over the roofs of the journal boxes.
12. A car truck side frame comprising a tension member formed with a substantially upright web portion and a lower flange, journal boxes at the ends of the frame, said lower flange meeting and integrally connected with each journal box and reinforced by ribs along the edge thereof adjacent the junctions with said journal boxes.
13. A car truck side frame comprising a tension member formed with a substantially upright web and a lower flange, journal boxes integrally connected at the ends of the frame and joined with said lower flange, ribs extending along the edges of said flange and continued along a wall of the adjacent journal box for reinforcing the junction therewith.
14. A car truck side frame comprising a tension member formed with a flange which is continued to and integrally joined with the adjacent wall of each journal box, said flange being reinforced along the free edges thereof by ribs angularly disposed with respect thereto and bridging the junctions between said flange and walls and continued along other walls of said journal boxes.

In testimony whereof I affix my signature.
MARK H. MARTIN.
